UNITED STATES PATENT OFFICE.

OLIVER S. SLEEPER, OF BUFFALO, NEW YORK, ASSIGNEE TO BUFFALO FOUNDRY & MACHINE COMPANY, OF BUFFALO, NEW YORK, A CORPORATION OF NEW YORK.

DISTILLING APPARATUS.

1,321,133.

Specification of Letters Patent. Patented Nov. 11, 1919.

Application filed January 28, 1918. Serial No. 214,100.

To all whom it may concern:

Be it known that I, OLIVER S. SLEEPER, a citizen of the United States, residing at Buffalo, in the county of Erie and State of New York, have invented new and useful Improvements in Distilling Apparatus, of which the following is a specification.

This invention relates to a distilling apparatus which is more particularly designed for distilling materials which condense and congeal at high temperatures, say above 212 degrees Fahrenheit, such as beta-naphthol, although the same may also be used for distilling other materials such for instance as, para - phenylene - diamin, diphenylamin, alpha-naphthylamin, beta-naphthylamin, alpha-naphthol, etc.

It is the object of this invention to produce a distilling apparatus whereby materials of this character may be distilled economically, expeditiously and safely and without encountering the usual difficulties attending the methods heretofore employed for distilling these materials, especially in subliming.

My invention has the further object to so organize the apparatus that the vapors of the material under treatment are positively prevented from reaching the vacuum pump or other exhausting device and also to prevent any of the neutralizing solution which is employed for protecting the vacuum pump against corrosion from flowing backwardly through the apparatus when the vacuum is broken and spoiling or undoing the work which has been accomplished.

In the accompanying drawings:

Figure 1 is a side elevation, partly in section, of a distilling apparatus embodying my invention. Fig. 2 is a front elevation, partly in section, of the same. Fig. 3 is a top plan view thereof.

Similar characters of reference refer to like parts throughout the several views.

The material to be treated is first heated so as to vaporize the same, this being best accomplished by placing the same in a retort 1 which has an opening 2 in its top through which the material to be treated is introduced into the retort and also an outlet 3 in its top through which the vapors escape from the retort. This filling opening is normally closed by cover 4. The heating of the retort may be effected in any suitable manner, this being effected for example, by

the means which are shown in the drawings and which comprise a furnace having a heating chamber 5 in which the lower part of the retort is arranged and a fireplace 6 in which fuel is burned for supplying the heat to the heating chamber.

As the vapors escape from the outlet of the retort they are received by a condenser which liquefies the same. In its preferred form this condenser comprises a pipe 7 which has a downwardly turned inlet end 8 connected with the outlet of the retort and a downwardly turned discharge or outlet end 9 and the body of this condenser pipe inclines from its inlet toward its outlet end, 70 as clearly shown in Fig. 1. After the vapors from the retort pass through this condenser the same become liquefied and flow from the inlet to the outlet end thereof.

10, 10 represent two receivers into one or the other of which the product of condensation from the condenser is discharged. These receivers are preferably arranged side by side and each of the same preferably comprises a hollow body 11 having an inlet at its front end which may be opened and closed by means of a lid or door 12 movably mounted on the body of the respective receiver and adapted to be tightly secured over the front opening thereof by any suitable means. At the lower end of the outlet the condenser is connected with inlets 14 in the top of the two receiving chambers by means of two branch pipes or conduits 13. The latter are connected with the outlet 90 of the condenser by means of a three-way valve 15 of any suitable construction so that the condenser may be placed in communication with either one of the branch pipes and disconnected from the other so that the condensation from the condenser flows into one of the receivers, thereby leaving the other receiver free to be opened for emptying, cleaning, etc. This three-way valve is preferably provided with a steam jacket or is otherwise heated so as to prevent the liquid while passing through this valve from freezing or solidifying therein and clogging the same. This is particularly important when distilling beta-naphthol which solidifies at a temperature of 20 degrees Fahrenheit.

In order to enable the attendant to observe the operation of the apparatus and note the character of the fluid as it enters 110

each receiver observation means are provided which preferably comprise a box forming a part of the respective branch pipe at the discharge end of the same and 5 a pair of observation windows 16, 16 arranged on opposite sides of this box thereby enabling the attendant to observe the character of the liquid which flows from each branch pipe into the respective receiver and 10 to operate the apparatus accordingly.

To facilitate the removal of the condensate from the receivers a pan 17 is placed in each receiver through the front opening thereof and in a position to receive the condensate entering through the top of the 15 receiver. When the pan in one receiver is filled to the desired extent with condensate the three-way valve 15 is turned so as to cut off this particular receiver from the 20 condenser and connect the latter with the other receiver, so that the further discharge of the condenser will be directed into the pan within the last mentioned receiver. This will leave the operator free to open 25 the receiver containing the filled pan and replace the filled pan therein with an empty one preparatory to again reversing the three-way valve when the pan in the receiver then in operation has been filled to the required 30 extent. This enables the apparatus to be operated without interruption until the batch of material under treatment has been completely distilled.

In order to expedite the distilling operation means are provided for producing a 35 vacuum in the receivers and the conduits connected therewith. This exhausting device withdraws from the receivers any uncondensed vapors and as the same in some 40 cases, for instance when distilling beta-naphthol, are more valuable than those which are collected in the pan 17, means are provided for recovering such vapors which escaped from the receivers. The 45 vapors in the case of beta-naphthol when leaving the receivers usually have the form of a fine snow or dust and the means for treating such dust laden vapors for separating and recovering this dust are preferably 50 constructed as follows:

18 represents a delivery pipe which has its inlet end provided with two branches 19, 19 connected respectively with the top or upper sides of the two receivers, each of 55 these branch pipes containing a valve 20 so that the delivery pipe may be connected with either one or the other of the receivers as required.

From the pipe 18 the uncondensed vapors 60 pass into a dry separator which is adapted to separate any dust or snow like product which may be present in the uncondensed vapor withdrawn by the exhausting device from one or the other of the receivers. This 65 dry separator preferably comprises a cham-

ber 21 which is provided with an inlet 22 and an outlet 23 on opposite sides of its upper part and a baffle 24 extending downwardly from the top of this chamber between its inlet and outlet. The inlet is connected with the discharge end of the delivery pipe 18 while the outlet of this chamber is subject to the influence of the exhausting device used in connection with this apparatus. As the uncondensed vapors pass 75 from the discharge pipe 18 into the upper part of the dry separator the same are interrupted by the baffle 24 which latter causes these vapors and any dust therein to be deflected downwardly toward the bottom of 80 this chamber, whereby the dust is separated from the uncondensed vapors and caused to settle or deposit on the bottom of this chamber while the uncondensed vapors pass upwardly along the opposite side of the baffle 85 and escape through the outlet on the opposite side of this chamber. The dust which gathers in the bottom of the dry separator is removed through a discharge passage or pipe 25 containing a valve 26 which controls this 90 exit. If this dust has solidified in the bottom of the chamber 21 the same can be melted by applying heat to the lower part of this chamber in any suitable manner so that the condensate flows in the form of a liquid 95 outwardly through this discharge pipe 25.

After the uncondensed vapors leave the outlet of the dry separator the same are passed through a trap which is designed to prevent any back flow of liquid or acid from 100 a point beyond this trap to the dry separator, receivers, condenser and retort. In its preferred form this trap comprises a chamber 60 having an inlet 27 in its top which is connected by a pipe 28 leading to the outlet of the dry separator and a discharge pipe 30 extending downwardly from the upper part or top of the chamber 60 but terminating short of the bottom thereof. The connecting pipe 28 contains a valve 29 105 whereby communication between the dry separator and the trap may be either maintained or interrupted. If desired any liquid which may get into the trap chamber 60 may be withdrawn through a pipe 31 connected 110 with the bottom thereof and containing a valve 32. The temperature of the chamber 60 may be controlled as desired by means of a jacket 33 surrounding the same and adapted to receive steam or other heating medium 115 if it is desired to prevent vapors passing through this chamber from congealing or a cooling medium such as cold water may be circulated through this jacket for the purpose of reducing the temperature of the 120 vapors passing through this chamber, the particular temperature changing medium which is circulated through the jacket 33 being governed by the character of the material under treatment. 130

The uncondensed vapors entering the trap chamber through the inlet at the top thereof pass downwardly through this chamber and thence upwardly through the outlet pipe 30 thereof and then are subjected to the separating action of a liquid separator or neutralizer which neutralizes any acid or corrosive medium in the vapors before the latter reach the vacuum pump or other exhausting device. This liquid separator or neutralizer comprises a chamber 34 having an outlet 35 in its top which is connected by means of a pipe 36 with the vacuum pump or other exhausting device and an inlet pipe 37 which extends downwardly from the top of this chamber and terminates at its lower end short of the bottom thereof while its upper end connects with the outlet pipe 38 of the trap. Within the lower part of the liquid separator is placed a charge of liquid solution which intercepts and neutralizes any acid or corrosive elements contained in the vapors which should not reach the vacuum pump. When distilling beta-naphthol the quantity of caustic soda solution placed in the lower part of the liquid separator is sufficient to submerge the lower end of the inlet pipe 37 and as the vapors pass from the inlet pipe 37 outwardly through this caustic soda solution to the outlet of the liquid separator, and any acid or corrosive element in the vapor is taken up by this solution, thereby preventing the same from reaching the vacuum pump and affecting the same injuriously. When desired the solution may be withdrawn from the lower part of the liquid separator 34 by means of a pipe 39 connecting with the bottom thereof and containing a valve 40. If for any reason the vacuum should be broken or the operation of the vacuum pump should be interrupted the backward pressure of air in the liquid separator would cause the caustic soda solution and acid therein to be forced outwardly therefrom into the lower part of the trap chamber 60 but since the inlet 27 of this last mentioned chamber is arranged at the top thereof the liquid which is drawn from the liquid separator into the trap cannot escape from the latter and reach either the dry separator, receivers, condenser or retort. The liquid separator therefore protects the pump against corrosion by acid or the like and the trap protects the retort condenser, receivers and dry separator from the effects of the caustic soda solution and the acid contained therein. It is therefore possible to operate this apparatus with perfect safety to all of its parts without liability of spoiling any of the condensate which has already been recovered, thereby facilitating the operation of the apparatus and reducing the cost of obtaining the distillate. The beta-naphthol condensate congeals

rapidly after entering the pan 17 and can be easily removed therefrom in the form of a cake by simply inverting the pan.

I claim as my invention:

1. A distilling apparatus comprising a 70 retort, a condenser connected with said retort, a receiver connected with said condenser, a separator comprising a chamber having an inlet and an outlet on opposite sides of its upper part and a baffle extending 75 downwardly from the top of said chamber between said inlet and outlet said inlet being connected with said receiver, and an exhausting device connected with the outlet of said separator.

2. A distilling apparatus comprising a 80 retort, a condenser connected with said retort, a receiver connected with said condenser, a separator comprising a chamber having an inlet and an outlet on opposite 85 sides of its upper part and a baffle extending downwardly from the top of said chamber between said inlet and outlet, said inlet being connected with said receiver, a trap comprising a chamber having an inlet 90 at its top which is connected with the outlet of said separator and an outlet pipe extending downwardly from above said trap chamber and stopping short of the bottom thereof, and an exhausting device connected 95 with said outlet pipe.

3. A distilling apparatus comprising a 100 retort, a condenser connected with said retort, a receiver connected with said condenser, a separator comprising a chamber 100 having an inlet and an outlet on opposite sides of its upper part and a baffle extending 105 downwardly from the top of said chamber between said inlet and outlet, said inlet being connected with said receiver, a trap comprising a chamber having an inlet 110 at its top which is connected with the outlet of said separator and an outlet pipe extending downwardly from above said trap chamber and stopping short of the bottom 110 thereof, a jacket inclosing said trap chamber and adapted to receive a temperature changing medium, and an exhausting device connected with said outlet pipe.

4. A distilling apparatus comprising a 115 retort, a condenser connected with said retort, a receiver connected with said condenser, a separator comprising a chamber having an inlet and an outlet on opposite 120 sides of its upper part and a baffle extending downwardly from the top of said chamber between said inlet and outlet, said inlet being connected with said receiver, a trap comprising a chamber having an inlet at its 125 top which is connected with the outlet of said separator and an outlet pipe extending downwardly from above said trap chamber and stopping short of the bottom thereof, a gravity liquid separator having an inlet connected with the outlet pipe of said trap, 130

and an exhausting device connected with said liquid separator.

5. A distilling apparatus comprising a retort, a condenser connected with said retort, a receiver connected with said condenser, a dry separator comprising a chamber having an inlet and an outlet on opposite sides of its upper part and a baffle extending downwardly from the top of said chamber between said inlet and outlet, a trap comprising a trap chamber having an inlet at its top which is connected with the outlet of said dry separator and having an outlet pipe extending downwardly from

the top of the trap chamber and terminating short of the bottom thereof, a liquid separator having a separating chamber adapted to receive liquid in its lower part and having an inlet pipe which connects with the outlet of said trap chamber and extends downwardly from the top of said liquid separating chamber but terminates short of the bottom thereof and which has an outlet at its top and an exhausting device connected with the outlet of said liquid separator. 15 20 25

OLIVER S. SLEEPER.

It is hereby certified that in Letters Patent No. 1,321,133, granted November 11, 1919, upon the application of Oliver S. Sleeper, of Buffalo, New York, for an improvement in "Distilling Apparatus," an error appears in the printed specification requiring correction as follows: Page 1, line 106, for the numeral "20" read ~~220~~; and that the said Letters Patent should be read with this correction therein that the same may conform to the record of the case in the Patent Office.

Signed and sealed this 2d day of December, A. D., 1919.

[SEAL.]

M. H. COULSTON,

Acting Commissioner of Patents.

Cl. 23—24.
